UNITED STATES PATENT OFFICE.

JACOB MANDEL, OF NEW YORK, N. Y.

SHEET-METAL BACKING-FRAME.

1,394,321.

Specification of Letters Patent.

Patented Oct. 18, 1921.

Application filed April 5, 1920. Serial No. 371,432.

To all whom it may concern:

Be it known that I, JACOB MANDEL, a citizen of the United States, and a resident of the city of New York, borough of Manhattan, in the county and State of New York, have invented a new and useful Sheet-Metal Backing-Frame, of which the following is a full, clear, and exact description.

This invention relates to backing frames for advertising cards, and has for an object to provide an improved construction in which a plurality of sheet metal members are telescopically arranged for receiving a single large card or a plurality of small cards without changing the general appearance of the device.

Another object of the invention is to provide a backing frame for advertising cards having a uniform edge so as to give the appearance of a complete frame for each card displayed.

A further object of the invention is to provide a backing frame for advertising cards which will present a complete frame inclosing the edges of the card when in operative position, and which may be adjusted to receive large or small cards without crimping the edges thereof.

In the accompanying drawing:

Fig. 1 is a front view of a sheet metal backing frame embodying the invention, the same being shown with a large and small card in place.

Fig. 2 is a sectional view through Fig. 1 on line 2—2.

Fig. 3 is a horizontal section through Fig. 1 on line 3—3.

Referring to the accompanying drawing by numerals, 1 and 2 indicate co-acting frame sections and 3 a partition plate bent substantially S-shape as indicated in Fig. 2, so that the upper edge of the lower card 4 will be fitted into the notch 5 and the lower edge of the upper card 6 fitted into the notch 7. The cards 4 and 6 are thus held in place properly and the partition plate is also held in position automatically without any particular fastening means. Frame section 1 is provided with a body or plate 8, which is turned over at the sides and front for presenting a frame structure 9 in which the side edges of the cards 4 and 6 extend as well as the bottom edge of card 4. Section 2 is also provided with a body or backing sheet 10 having bent over edges so as to represent a frame 11, in which the side edges

of card 6 and the upper edge of card 6 fit. The section 2 is of slightly less width than section 1 so as to telescope therein, as indicated in Fig. 1. In order to hold these sections together and yet allow a certain telescoping action, slots 12 and 13 are provided in body 8 and pressed out guiding members or hooks 14 and 15 extend from the body 8 of the section 1. This arrangement holds the two sections together while allowing a telescoping movement for permitting the frame sections to properly fit one or more cards.

When it becomes necessary to put two cards in place, as for instance cards 4 and 6, the section 2 is moved so as to produce as big a frame inclosure as possible, after which the card 4 is bowed slightly and the edges forced into the side turned over flanges 9 of section 1. The card is then slid down until the lower edge is properly fitted into the lower edge of the bottom frame after which the plate 3 is placed in position as shown in Figs. 1 and 2. The space above this plate is larger than card 6 so that card 6 may also be bowed sufficiently to cause the edges to enter the turned over edges 9 and 11. After this has been done the card is moved downwardly until it engages the plate 3 after which the section 11 is forced downwardly until it fits properly over the upper edge of the card. By this operation both cards are placed in position without crimping any of the edges and yet a proper frame is provided for each card without any extra space left over.

In the drawing two cards have been shown in one frame, each card having a sort of frame of its own. By adding another plate 3 three cards could be used, or even more if additional plates were used, though ordinarily two or three cards is all that will be placed in one frame. In some instances only one card is desired, when this is the case the plate 3 is removed and the sections 1 and 2 moved apart as far as possible and a single card placed in position after which the sections are telescoped together or at least a sufficient distance toward each other to fit properly over the single card. The device may be mounted in a car or at any place desired by suitable securing members clamped over both sections, or merely over the lower section 1 as may be preferred. The easy and quick adjustability of the parts permit a quick

and easy substitution of new cards whenever desired and which is quite often done when advertising seasonable goods.

What I claim is:

5 A backing frame for advertising cards comprising a frame formed from two telescoping sections, each section having bent over edges producing an annular groove when the sections are fitted together, means
10 extending from one of said sections interlocking with the other section for limiting the telescoping action of the respective sec-

tions in both directions and a partition plate fitting against one of said sections and formed substantially S-shaped in cross section with one face conforming to the appearance of the bent over edges of the frames, said S-shaped partition formed with opposite facing grooves for receiving upper and lower cards, said cards being positioned to 20 extend into said annular groove and into said oppositely facing grooves whereby said partition plate is held in place in said frame.

JACOB MANDEL.
